GLASS VASE OR SIMILAR ARTICLE

Charles W. Carlson, Tiffin, Ohio

Application March 9, 1951, Serial No. 14,445

Term of patent 14 years

(Cl. D36—8)

To all whom it may concern:

Be it known that I, Charles W. Carlson, a citizen of the United States, residing in Tiffin, Ohio, have invented a new, original, and ornamental Design for a Glass Vase or Similar Article, of which the following is a specification, reference being had to the accompanying drawing, forming part thereof.

In the drawing:

Fig. 1 is an elevational view of a glass vase, showing my new design;

Fig. 2 is a similar elevational view taken at an angle of approximately 60° to Fig. 1;

Fig. 3 is a horizontal cross-sectional view on the line III—III of Fig. 1; and

Fig. 4 is a horizontal cross-sectional view on the line IV—IV of Fig. 1.

The dominant features of the design reside in the part drawn in full lines, as shown in the drawing.

I claim:

The ornamental design for a glass vase or similar article, as shown and described.

CHARLES W. CARLSON.
